Patented Sept. 14, 1926.

UNITED STATES PATENT OFFICE.

CLYDE ELLIS, OF CHICAGO, ILLINOIS.

CENTRIFUGAL VENTILATOR.

Application filed March 26, 1926. Serial No. 97,712.

This invention relates to ventilators, and more particularly to what I term a centrifugal ventilator for use on railway dining cars.

5 One of the main objects of the invention is to provide a ventilator of simple and inexpensive construction which may be readily mounted in the window of a dining car and, during travel of the car, will force air into 10 the car from outside thereof. A further object is to provide a ventilator which will operate equally well when the car is travelling in either direction. Further objects will appear from the detailed description.

15 In the drawings:

Fig. 1 is an inner front view of the ventilator.

Fig. 2 is a central vertical longitudinal section through the ventilator.

20 Fig. 3 is a top plan view of the ventilator.

Fig. 4 is a longitudinal horizontal section through the ventilator, parts being shown in elevation.

Fig. 5 is an outer face view of the ventilator.

Fig. 6 is a section taken substantially on line 6—6 of Fig. 4.

Fig. 7 is a section taken substantially on line 7—7 of Fig. 4.

30 Fig. 8 is a fragmentary section through the ventilator fan hub.

The ventilator includes a box like casing 1 which is divided by partitions 2 into end compartments 3 and a center compartment 4. A shaft 5 is rotatably mounted through each end compartment 3 and two wind wheels 6 are secured on this shaft, each wheel including disks 7 between which are mounted vanes 8 disposed radially of the wheel, the outer end of each vane being turned inwardly substantially at right angles to provide an end flange 9. A hub 10 is mounted on shaft 5 between wheels 6 and is provided with a central groove which receives a cord 11 which passes about hub 12 of a ventilator fan 13, hub 12 being provided with spaced grooves 14 for the reception of the cords 11.

40 Fan 13 is rotatably mounted on a shaft 15 secured through front and back supporting strips 16 and 17, respectively, extending from the top to the bottom of the casing 1, this shaft being positioned centrally of the center compartment 4. The front or inner side of compartment 4 is closed by a suitable screen 18 and the outer ends of compartments 3 are closed by screens 19. The cas-

ing is further provided with closure members or doors 20 positioned above compartments 3 and hingedly secured at their outer ends, at 21, to the top wall of the casing. 60

In using the ventilator it is mounted in position upon the window sill so as to project outwardly beyond the side of the car. If the car is travelling in the direction indicated by the arrow in Figure 2, door 20 at 65 the left hand end, as considered in this figure, is opened, the other door 20 being closed, this permits air to flow downwardly through the left hand end compartment 3, this air escaping from this compartment 70 through screen 19. The air strikes the vanes of wind wheel 6 thus rotating the same and, by means of the belt 11 rotating fan 13. The fan 13 when thus rotated will cause a current of air to flow into the car so as to 75 ventilate the same. When travelling in the opposite direction door 20 at the left hand end of the housing as considered in Figure 2 is closed, the door at the right hand end of the housing being opened. In this case the 80 fan will be rotated in the other direction and will act as a suction fan so as to remove heated air, smoke, etc., from the interior of the dining car, causing fresh air to enter the car through the ventilators at the top 85 thereof usually provided for this purpose. The fan 13 is rotated and acts to cause a current of air to flow through the car thus obtaining a very decided cooling 90 effect and very efficient ventilation of the car. In practice I will mount a ventilator in each window of the car and the combined effect of these ventilators is sufficient to very materially cool the entire interior of the car, obtaining thorough ventilation thereof and 95 removing any vapors, heated air and other products caused by cooking on the ranges of the dining car.

As will be noted more clearly from Figures 4 and 5, I provide opening 22 through 100 the back or top wall of each end compartment 3, these openings permitting the escape of cinders or other foreign materials. Such materials can readily escape from the center compartment 4 as the outer side of 105 this compartment is open except for the provision of the central supporting strip 17.

What I claim is:

1. In a ventilator of the character described, a casing divided into a central compartment and two end compartments, a fan mounted in the central compartment, wind 110

wheels mounted in the end compartments, driving connections between the wind wheels and the fan, the outer ends of the end compartments communicating with the atmosphere, and means for optionally opening or closing the top of either of the end compartments selectively.

2. In a ventilator of the character described, a box like casing divided into a central compartment and two end compartments, the end compartments communicat-

ing at their outer ends with the atmosphere, wind wheels mounted in the end compartments, a fan mounted in the central compartment, driving connections between the wind wheels and the fan, and doors for optionally opening or closing the upper ends of either of the end compartments, selectively. ¹⁵

In testimony whereof I affix my signature.

CLYDE ELLIS.
